UNITED STATES PATENT OFFICE

CARL HORIX, OF CHICAGO, ILLINOIS

BELT BUCKLE

Application filed December 21, 1927. Serial No. 241,476.

This invention relates to expandible holding devices for belts to be worn about the waist and is in the nature of an improvement on the device of my prior application, Serial No. 146,916, filed November 8, 1926.

One object of the invention is to provide an expandible belt buckle which shall be of improved construction and operation.

A further object of the invention is to provide an expandible belt buckle having resilient means so disposed as to be practically invisible, and so as not to interfere with the position of the belt or the operation of the belt buckle, and so as not to irritate or inconvenience the wearer.

A further object is to provide an improved method of constructing a buckle of the class named.

Other objects and advantages will appear from the following description.

The invention is exemplified in the combination and arrangement of parts shown in the accompanying drawing and described in the following specification, and it is more particularly pointed out in the appended claims.

In the drawing—

Fig. 1 is a front elevation of a belt buckle comprising the present invention and attached to a belt;

Fig. 2 is a section on line 2—2 of Fig. 1;

Fig. 3 is a section on line 3—3 of Fig. 2;

Fig. 4 is a section on line 4—4 of Fig. 3; and

Fig. 5 is a plan of the blank from which the body of the buckle is formed.

Figs. 3, 4 and 5 are on an enlarged scale.

In the drawing, the numeral 10 designates a buckle plate or body having flanges 11 bent backwardly at opposite edges thereof, the rear edges of the flanges being rolled inwardly to form tubular housings 12 which are spaced rearwardly from the plate, as shown clearly in Figs. 2 and 3.

When the plate 10 is blanked out, eyelets 13 are punched in the plate near the opposite edges thereof in position to be disposed on the inner faces of the housings 12 when the edges are rolled up to form the completed buckle. Spaced projections 14 are also formed on the blank in position to project from one edge of

each tubular housing. The tubular housings 12 may be circular or slightly elongated in cross-section, as shown in Fig. 3.

Compression springs 15 are provided with bars 16 which extend through the springs, each bar having a head 17 at one end for engaging one end of the spring. After the tubular housings 12 have been formed, the projections 14 are bent inwardly to provide a restricted opening at one end of each of the housings of sufficient size to admit the bar 16 but to retain the springs 15 against endwise movement from the end of the housing. The springs 15 and bars 16 are inserted in each of the housings 12 through the open ends thereof and the ends of the bars are projected from the restricted openings formed by the inwardly bent lugs 14. The projecting ends of the bars 16 are then formed about lugs 18 on an attachment loop 19 to which the end of the belt 20 is detachably secured by snap fasteners 21. A buckle tongue 22 is provided with a loop 23 which extends about a pivot pin 24. The pin 24 is journaled in the eyelets 13. The tongue may be first looped about the pin 24 and the sides 11 may then be spread slightly to permit the insertion of the pin 24, after which they are forced inwardly to their normal position to prevent the escape of the pin 24 from its support.

The front edge of the tongue 22 engages the rear face of the belt 20, the tongue being disposed at an oblique angle to the surface of the belt and being inclined toward the loose end of the belt so that tension on the belt presses the end of the tongue more tightly against the face of the belt. A lever member 25 is formed continuously with the tongue 22 and loop 23 and may be tapered to provide a contact end for engaging the face of the belt. The parts are so proportioned that the edge of the tongue will strike the face of the belt before the lever 25 engages the belt and when the lever is pressed into contact with the belt, the edge of the tongue will slightly compress the belt so that it will be sufficiently imbedded in the surface of the belt to secure a firm grip thereon.

The position of the eyelets 13 on the inner faces of the housings 12 permits the tongue

to be pivoted between the housings without any pivotal support or other projection extending rearwardly beyond the surfaces of the housings. The spaced relation of the 5 housings 12 to the plate 10 permits the edges of the belt to underlie the housings so that the buckle is but very slightly wider than the belt itself. It will be noted that all of the moving parts are concealed by the belt and the buckle has the appearance of a buckle of usual construction.

The form of housing and attachment for the springs 15 makes it possible to manufacture the buckle with a minimum of labor and 15 expense and to employ springs under compression which automatically limit the amount of yielding movement to an amount determined by the size and proportions of the parts. The buckle may be readily detached 20 from the belt and applied to other belts, as desired.

I claim:

1. A belt buckle comprising a plate, housing members spaced rearwardly from said 25 plate and extending adjacent opposite edges thereof, springs disposed in said housing members, said springs being adapted to have one end of a belt attached thereto, and a holding device pivotally mounted between the 30 inner faces of said housing members and disposed entirely in front of the plane of the rear faces of said housing members for holding the other end of said belt against the rear face of said plate.

35 2. A belt buckle comprising a plate having opposite edges thereof bent rearwardly, tubular housing members projecting inwardly from the rearwardly bent portions of said plate and spaced from the rear face of said 40 plate, yielding means in said housing members adapted to be connected to one end of a belt, said housing members having aligned pivotal openings in the inner faces thereof and disposed in front of the plane of the rear 45 edges of said housing members, a pin having its opposite ends disposed in said openings, and a holding tongue mounted on said pin for engaging the other end of said belt.

3. A belt buckle comprising a plate having 50 a pair of tubular housing members mounted at opposite edges thereof and spaced rearwardly from said plate, each of said housing members having a restricted opening at one end thereof, a spring disposed in each of 55 said housing members and bars each having one end thereof held by said springs and the opposite end thereof extending through one of said restricted openings, the projecting ends of said bars being adapted to have one 60 end of a belt attached thereto and holding means for holding the other end of said belt against the rear face of said plate.

65 4. In combination, a belt buckle comprising a plate, tubular housing members disposed adjacent opposite edges of said plate

and spaced rearwardly from the rear surface of said plate, each of said tubular housing members having one end thereof open and the opposite end thereof partially closed, helical springs disposed in each of said housing members, rods extending through said springs and having heads on the ends thereof adjacent the open ends of said housing members for engaging the ends of said springs respectively, the ends of said rods opposite their heads extending through the restricted openings in the ends of said housing members, a belt having one end thereof attached to the projecting ends of said rods, and means disposed between said housing members for clamping the opposite end of said belt to said plate.

5. A belt buckle comprising a plate having portions on opposite edges thereof rolled to form tubular housing members, springs in 85 said housing members to which one end of a belt is adapted to be attached, said portions having perforations therethrough arranged to be brought into registration when said portions are rolled to form housing members, 90 and a releasable holding tongue pivotally supported by means mounted in said perforations, said holding tongue being held against bodily movement by said perforations and adapted to hold the other end of 95 said belt against the rear face of said plate.

6. A belt buckle comprising a plate having portions adjacent opposite edges thereof rolled to form tubular housing members, said portions having pivot supports arranged to be brought into registration when said portions are rolled to form said housing members, a holding device mounted in said pivot supports for holding one end of a belt against the rear face of said plate, projections 100 on said plate at one end of each of said rolled portions arranged to be bent inwardly to form restricted openings at the ends of said tubular housing members, springs disposed in said tubular housing members, pull rods connected with said springs and projecting from the restricted openings at the ends of said housing members, and means on the projecting ends of said pull rods to which the other end of said belt may be attached.

In testimony whereof I have signed my name to this specification on this 16th day of September, A. D. 1927.

CARL HORIX.
